(57) **CLAIM**

I claim, the ornamental design for a foam insert for residual limb casting, as shown and described.

DESCRIPTION

FIG. 1 is a top perspective view of a foam insert for residual limb casting showing the claimed design.

FIG. 2 is a front view of the foam insert for residual limb casting illustrated in FIG. 1.

FIG. 3 is a rear view of the foam insert for residual limb casting illustrated in FIG. 1.

FIG. 4 is a right side view of the foam insert for residual limb casting illustrated in FIG. 1.

FIG. 5 is a left side view of the foam insert for residual limb casting illustrated in FIG. 1.

FIG. 6 is a top view of the foam insert for residual limb casting illustrated in FIG. 1.

FIG. 7 is a bottom view of the foam insert for residual limb casting illustrated in FIG. 1; and,

FIG. 8 is another perspective view of the foam insert for residual limb casting of FIG. 1 but in an intended environment receiving a residual leg.

The broken lines in the figures show portions of the foam insert that form no part of the claimed design.

1 Claim, 7 Drawing Sheets
